(57) **CLAIM**

The ornamental design for a sanitizer case for mobile devices, as shown and described.

DESCRIPTION

FIG. 1 is a front perspective view of the sanitizer case for mobile devices;

FIG. 2 is a front elevational view of the sanitizer case for mobile devices of FIG. 1;

FIG. 3 is a rear elevational view of the sanitizer case for mobile devices of FIG. 1;

FIG. 4 is a left-side elevational view of the sanitizer case for mobile devices of FIG. 1;

FIG. 5 is a right-side elevational view of the sanitizer case for mobile devices of FIG. 1;

FIG. 6 is a top planar view of the sanitizer case for mobile devices; and,

FIG. 7 is a bottom planar view of the sanitizer case for mobile devices.

The broken lines in the drawings depict portions of the article that form no part of the claimed design. Additionally, any unshaded surface directly adjacent to the broken lines forms no part of the claimed design.

1 Claim, 5 Drawing Sheets
